UNITED STATES PATENT OFFICE.

CHARLES H. WEST, OF PITTSBURGH, PENNSYLVANIA, ASSIGNOR TO WESTMORELAND GLASS COMPANY, OF GRAPEVILLE, PENNSYLVANIA, A CORPORATION OF PENNSYLVANIA.

DESIGN FOR A CANDLESTICK.

Application filed March 1, 1926. Serial No. 16,705. Term of patent 7 years.

To all whom it may concern:

Be it known that I, CHARLES H. WEST, a citizen of the United States, residing at Pittsburgh, in the county of Allegheny and State of Pennsylvania, have invented a new, original, and ornamental Design for a Candlestick, of which the following is a specification, reference being had to the accompanying drawing, forming part thereof, in which:

I claim:

The ornamental design for a candlestick as shown.

CHARLES H. WEST.
